F. LJUNGSTRÖM.
MEANS FOR SECURING TURBINE ROTORS TO THEIR SHAFTS.
APPLICATION FILED APR. 15, 1919.

Patented July 20, 1920.

Inventor:
Fredrik Ljungström,
by
Albert G. Orvis
His Attorney.

UNITED STATES PATENT OFFICE.

FREDRIK LJUNGSTRÖM, OF BREVIK, LIDINGÖN, SWEDEN, ASSIGNOR TO AKTIE-BOLAGET LJUNGSTRÖMS ANGTURBIN, OF STOCKHOLM, SWEDEN, A CORPORATION.

MEANS FOR SECURING TURBINE-ROTORS TO THEIR SHAFTS.

1,347,344.

Specification of Letters Patent.

Patented July 20, 1920.

Application filed April 15, 1919. Serial No. 290,355.

To all whom it may concern:

Be it known that I, FREDRIK LJUNGSTRÖM, a subject of the King of Sweden, residing at Brevik, Lidingön, Sweden, have invented 5 certain new and useful Improvements in Means for Securing Turbine-Rotors to Their Shafts, of which the following is a specification.

The present invention relates to means for 10 securing turbine rotors to their shafts and has for its object to provide an improved structure and arrangement for keeping the parts tight at all times.

For a consideration of what I believe to be 15 novel and my invention, attention is directed to the accompanying description and the claims appended thereto.

In the drawing which illustrates an embodiment of my invention, the figure is an 20 axial, sectional view of a part of a turbine shaft and a rotor carried thereby.

Referring to the drawing, 1 indicates a 25 part of a rotor upon which are mounted concentric rows of blades 2. In the type of turbine to which my invention more especially relates, two rotors are provided arranged face to face with concentric rows of axially extending blades between and through which the steam flows radially outward. The 30 rotor is provided with a hub 3 containing slots 4 through which steam flows from a suitable source to the inner blade ring. The hub 3 is provided with a conical bore to receive one end of a stub shaft 5 and the two 35 parts are held against relative rotation by a plurality of spaced keys 6 which may be made advantageously of round stock finished to the required size. These keys have a slight taper from their inner to their outer 40 ends so that when moved outwardly from the center of the machine they will prevent any play from existing in the key slots.

Stub shaft 5 is made hollow and inside of 45 it is a tubular tension member 6^a. Tubular member 6^a is connected at its outer end to stub shaft 5 by a threaded engagement as indicated at 7. At its inner end tubular member 6^a is provided with a flange or shoulder 8 which engages hub 3 to hold it on the tapered end of stub shaft 5. By turning the 50 tubular member 6^a the threaded engagement 7 will pull flange 8 into engagement with hub 3, thereby firmly pulling the hub on the end

of the stub shaft and at the same time putting the member 6^a under tension. 55

By calculation or experiment, or both, it is determined how much the bore of the hub will enlarge due to temperature changes. It is evident that if the hub expands more quickly than the shaft it will become loose. 60 It is further evident since the contacting surfaces of the shaft and the wall of the bore are conical that the parts can again be made tight if, when the hub expands, the shaft and the hub are drawn together. This function is performed by the tension member 6^a. 65 Having determined what the maximum enlargement of the hub will be and how much axial movement is necessary to bring the parts into firm contact under all conditions, 70 the tension member is so designed that it will, when cool, be stretched by an amount somewhat greater than the total amount of the relative axial movement between the hub and stub shaft at any time. As a result of 75 this, when the hub enlarges for any reason the tension member will force the hub farther onto the shaft with the effect of keeping it tight. To state the matter in another way, the tension member is always seeking 80 to shorten itself and will do so whenever there is the slightest looseness between the hub and the shaft.

The member 6^a is made hollow and is provided with an end wall 10 in which is a hole 11 to allow steam to enter the hollow stub shaft 5. A nut 12 is provided for the purpose of preventing steam from passing into the joint between the stub and the main shafts. 85

With this arrangement steam may pass 90 through tension member 6^a into the hollow shaft 5 so as to heat it, thereby tending to keep its temperature substantially the same as that of the hub 3. By this arrangement 95 the hub 3 and stub shaft 5 will tend to expand and contract with temperature changes at substantially the same rate.

The present invention is a modification of 100 and relates to apparatus of the character shown in the earlier application of Birger Ljungstrom, Sr. No. 285,032, filed March 25, 1919, means for securing turbine rotors to their shafts.

In accordance with the provisions of the 105 patent statutes, I have described the pri-

ciple of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

- 10 1. In a turbine, the combination of a rotor, a hollow shaft having a tapered end to which the rotor is keyed, and a hollow tension member having a fixed flange on its inner end which engages said rotor, the outer end of said member being connected to said

rotor for putting such member under tension.

2. In a turbine, the combination of a rotor, a hollow shaft having a tapered end to which the rotor is keyed, and a hollow tension member having a flange on its inner end which engages said rotor, the outer end of said member having threaded engagement with said hollow shaft.

In testimony whereof I affix my signature 25 in presence of two witnesses.

FREDRIK LJUNGSTRÖM.
